UNITED STATES PATENT OFFICE.

ALEXANDER PIERREPOINT DEROCHE, OF OTTAWA, ONTARIO, CANADA.

SLEEPING-CAR.

1,242,331.

Specification of Letters Patent.

Patented Oct. 9, 1917.

Application filed June 26, 1917. Serial No. 177,113.

To all whom it may concern:

Be it known that I, ALEXANDER PIERREPOINT DEROCHE, a subject of the King of Great Britain, and a resident of the city of Ottawa, in the Province of Ontario and the Dominion of Canada, have invented certain new and useful Improvements in Sleeping-Cars, of which the following is a specification.

10 This invention relates to improvements in sleeping cars of the type having upper and lower berths, and the objects of the invention are to provide a convenient dressing compartment for the use of the occupant of 15 the upper berth, whereby the upper berth may be rendered more desirable and comfortable for the user.

Further objects are to enable the occupants of the upper berth to easily mount 20 the same without the use of a separate ladder and without disturbing the occupant of the lower berth.

Further objects are to generally simplify 25 and improve the construction to enable the occupants of the upper berth an increased air space and better ventilation with a greater degree of privacy and safety.

Still further objects of the invention are 30 to enable the foregoing objects to be obtained without reducing appreciably the available berth space of the car.

It has already been proposed to provide dressing compartments between adjacent sections of a sleeping car, but such compartments have formed permanent lost space 35 in the car, whereas according to the present invention, the space which forms the compartment when the berth is made up is used in the daytime as part of the seating 40 space.

According to the present invention the seating is re-arranged to provide a somewhat greater space between the seats and partitioning means are provided, whereby, 45 when the berths are made up, a dressing compartment may be provided for the upper berth including steps by which the occupant may enter the same.

For a complete description of the inven-

tion however reference is made to the following specification and drawings.

In the drawings,

Figure 1 is a longitudinal vertical section of a car embodying the present invention showing the berths made up. 55

Fig. 2 is a transverse section indicating the day coach arrangement.

Fig. 3 is a longitudinal section of the day coach arrangement.

Fig. 4 is a plan partially in section of the 60 night coach arrangement.

Fig. 5 shows a detail of the supporting counter levers.

In the drawings like characters of reference indicate corresponding parts in all 65 the figures.

Referring to the drawings, A represents a car the general construction and arrangement of which may be of any approved standard design. 10 represents the back 70 portions of the seats which abut back to back on opposite sides of separating partition 13.

The horizontal portions 11 of the seats B and C are adapted to slide toward each other to form a support for the mattress 75 D when the lower berth is made up. It may be said, however, that the constructions of the seat and the mode of supporting and mounting the same are the same as that at present adopted in standard sleeping cars, 80 the portions 11 of the seat being mounted on suitable counter lever arms 12, which are supported in a well known manner. As illustrated each arm is formed with a groove 12^a to receive fixed pins 12^b in frame and 85 groove 12^c to receive sliding pins 12^d on the movable seat.

The upper berth E is pivoted to the side of a car in the usual manner and supported at the outside by folding levers 14. It is 90 somewhat shorter than the space between the partitions 13. Partitioning means F, which may be a collapsible partition of wood, are adapted to extend from one end of the berth to the bottom of the lower 95 berth, the other end of the upper berth being adapted to abut the partition G, which is adapted to be placed in position and ex-

tends upwardly from the top of the partition 13.

The bottom of the partition F is adapted to be inserted between portions 10 and 11 of the seats C when placed horizontally, being suitably supported by the frame 25 of the seat. It will be apparent, however, that there are many ways of connecting and supporting the partitioning means in position.

When the upper berth is lowered the curtain rod 26 of usual form will be swung into position in the usual way. It is necessary, however, to provide it with a sliding extensible telescopic end piece 27 to extend over the space between the end of the upper berth and the partition G.

It will be seen that the partitioning means F leaves a compartment H extending from the level of the lower seat to the upper berth which may be used as a dressing compartment by the occupant of the upper berth. To assist the occupant of the upper berth in mounting to the same, a sliding lower step 16 may be provided adapted to slide into the frame of the seat and additional steps or platforms 17 and 18 may be provided of the removable form and shape indicated. These steps, it will be seen, extend between the partition F and the partitions 13 and G.

If desired suitable folding hooks 19 may be provided on the partition G for the convenience of the occupant of the upper berth.

It will be seen that by the arrangement above described, the occupant of an upper berth can:

1. Easily mount to the upper berth without the aid of a ladder.
2. Retire without disturbing occupant of lower berth.
3. Stand upright with ample space and headroom for dressing, or
4. Sit down for the same purpose, without being disturbed by passers through the aisle.
5. Hang all apparel up on hooks in the ordinary way, without folding or crowding them.
6. Enjoy greater privacy and safety in the upper berth.
7. Enter berth from end thereof.

For the above reasons it is claimed for this invention that the present great objection to upper berths will be removed, rendering them equally desirable to the lower berths, thereby providing a much greater percentage of desirable space in each car for each occupant thereof.

By the popular acceptance of the upper berth the railway will be in a position to:

1. Increase the tariff for the upper berth at least equal to or greater than that charged for the lower berth.

2. Sell each car to its full capacity, the revenue from which will greatly exceed that of the present standard sleeping car with its present average of unoccupied upper berths.

3. Reduce the unnecessary haulage and maintenance of extra sleeping cars at present necessitated by the demand for lower berths.

4. Increase the revenue and reduce the haulage with the same locomotive power.

5. Increase terminal, round-house and yard facilities by transporting fewer cars.

6. Eliminate duplication of linen, bedding, and similar accessories which have to be carried at present for unused upper berths.

7. Proportionately reduce the number of porters and attendants.

8. Facilitate making and breaking of berths.

9. Increase the space between the seats and thereby add appreciably to the comfort of day traffic.

When it is considered that the unnecessary transport of one car involves a cost of 20¢ per mile for haulage alone, the actual saving involved by carrying only completely filled cars, from an economical standpoint is of vital importance.

As many changes could be made in the above construction and many apparently widely different embodiments of my invention within the scope of the claims constructed without departing from the spirit or scope thereof, it is intended that all matter contained in the accompanying specification and drawings shall be interpreted as illustrative and not in a limited sense.

What I claim as my invention is:

1. A sleeping car having seats arranged in pairs, each seat being formed with a lower horizontal portion and an upper vertical portion, partitions separating the seats in adjacent pairs, the said upper and lower portions of the seats being adapted to be moved to form a support for the mattress of the lower berth, an upper berth pivotally mounted above the lower berth, and of less length than the same, a second partitioning means extending from the partition between the seats upwardly and a third partitioning means extending between the upper and lower berths and forming a compartment at the end of the lower berth for the use of the occupant of the upper berth, said partition being adapted to fit between the two sections of one of the seats.

2. A sleeping car having sections, each comprising an upper and a lower berth, the length of the upper berth being shorter than that of the lower berth, partitioning means extending between the end of the upper berth and the lower berth and forming a

compartment for the use of the occupant of the upper berth.

3. A sleeping car having sections each comprising an upper and a lower berth, the 5 length of the upper berth being shorter than that of the lower berth, partitioning means extending between the end of the upper

berth and the lower berth and forming a dressing compartment for the occupant of the upper berth and platforms in said compartment. 10

In witness whereof I have hereunto set my hand.

ALEXANDER PIERREPONT DEROCHE.
